Primary Examiner—Alan P. Douglas*Assistant Examiner*—Robin V. Taylor**[57]****CLAIM**

The ornamental design of hand winch, as shown and described.

DESCRIPTION

FIG. 1 is a front view in elevation of a hand winch of the present invention;

FIG. 2 is a side view in elevation of the hand winch of FIG. 1 as seen from the right-hand side FIG. 1;

FIG. 3 is a side view in elevation of the hand winch of FIG. 1 as seen from the left-hand side of FIG. 1;

FIG. 4 is a bottom plan view of the hand winch of FIG. 1;

FIG. 5 is a top plan view of the hand winch of FIG. 1;

FIG. 6 is a rear view in elevation of the hand winch of FIG. 1;

FIG. 7 is a front elevation of the hand winch of the present invention with a handle attached to the hand winch base plate, the latter being indicated in broken lines; and.

FIG. 8 is a rear view in elevation of the hand winch of FIG. 1 without the base plate.

In the above illustrations, the broken line showing a hand winch base plate is for illustrative purposes only and forms no part of the claimed design.
